US0D1107830S

(12) **United States Design Patent** (10) **Patent No.:** **US D1,107,830 S**
(45) **Date of Patent:** **** Dec. 30, 2025**

(54) **DUMBBELL**

(71) Applicant: **Personality Gym AB**, Jönköping (SE)

(72) Inventor: **Tomas Svenberg**, Jönköping (SE)

(**) Term: **15 Years**

(21) Appl. No.: **35/522,086**

(22) Filed: **Apr. 8, 2024**

(80) **Hague Agreement Data**

Int. Filing Date: **Apr. 8, 2024**

Int. Reg. No.: **DM/239207**

Int. Reg. Date: **Apr. 8, 2024**

Int. Reg. Pub. Date: **Aug. 23, 2024**

(51) **LOC (15) Cl.** **21-02**

(52) **U.S. Cl.**

USPC **D21/681**

(58) **Field of Classification Search**

USPC D21/675, 680, 681, 682, 684

CPC A63B 21/075; A63B 21/072
